Attorney

UNITED STATES PATENT OFFICE.

EDWARD L. STAHLER, OF HAMMOND, INDIANA, ASSIGNOR OF ONE-HALF TO FRED. A. SEBENSTE, OF HAMMOND, INDIANA.

MEASURING AND FILLING DEVICE.

Application filed October 18, 1923. Serial No. 669,342.

To all whom it may concern:

Be it known that I, EDWARD L. STAHLER, a citizen of the United States, residing at Hammond, in the county of Lake and State 5 of Indiana, have invented certain new and useful Improvements in Measuring and Filling Devices, of which the following is a specification.

My invention relates to improvements in 10 measuring and filling devices and particularly that type which is adapted to be used in ice cream dispensing.

An important object of this invention is to 15 provide a device which will quickly measure and transfer commonly used quantities of ice cream, such as pints and quarts without waste.

A further object of the invention is the 20 provision of a dispensing device which will quickly and conveniently fill the cylindrical containers very commonly used.

A further object of the invention is to provide a measuring and filling device which is 25 simple and durable of construction and comparatively inexpensive to manufacture.

Other objects and advantages of this invention will be apparent during the course 30 of the following description.

In the accompanying drawing forming a 35 part of this specification and in which like numerals are employed to designate like parts throughout the same,

Figure 1 is a top plan view,

Figure 2 is a vertical sectional view taken 40 on line 2—2 of Figure 1,

Figure 3 is a side elevation of the device, and

Figure 4 is a horizontal section taken on 45 line 4—4 of Figure 2.

In the drawing, wherein for the purpose 50 of illustration is shown the preferred embodiment of my invention, the numeral 10 designates a cylindrical shell forming the body of the device, the lower portion thereof being open as at 11, while the upper portion 55 12 is closed with the exception of an aperture to permit movement of a plunger rod therein, and a plurality of openings 13 to permit the exhaust of air therefrom. At the lower portion of the shell 10, a wire 14 is tightly drawn diametrically across the shell and riveted or otherwise secured to the shell as at 15.

In order to force the merchandise from 55 within the shell 10, a plunger 16 is mov-

ably fitted therein and provided with a packing ring 17 which insures a tighter connection and prevents the passage of matter between the plunger head and the shell. The plunger head 16 is provided also 60 with a plurality of apertures 18 which permit the escape of air upon filling the cylindrical shell. The plunger head 16 is actuated by a plunger rod 19 which is preferably formed integral with the plunger head 65 and has a vertical bore drilled therein to permit a cutter rod 20 to pass through same in order to rotate the cutter blade 21. The upper portion of the plunger rod 19 is threadedly connected to a gripping handle 70 22 which carries a collar 23 which rotates on ball bearings 24. A hand wheel 25 is secured to the cutter rod 20 by a nut 26, said hand wheel resting upon the collar 23 and revolving upon the ball bearings 24. 75 To permit adjustment of the plunger head within the shell, a plurality of notches 27 are formed in the plunger rod 19 and adapted to engage a sliding bolt 28 which slides in the latch member 29.

In operation, the device when used for dispensing ice cream for which it is particularly adapted, is regulated by inserting the sliding bolt 28 into the proper notch according as to whether a pint or quart of the 80 cream is to be measured. The next operation is to force the device downwardly into a can of cream until the shell has been 85 filled, the entire device then being turned two or three complete revolutions, permitting the wire 14 to cut the cream within the shell and permit same to be separated from the general mass in the can. The device is then withdrawn from the can of ice cream and positioned over the container, said container usually being cylindrical in form. The ice cream is then forced from the shell by releasing the sliding bolt 28 and forcing the plunger head 16 downwardly by means 90 of the plunger rod 19 and handle 22.

It is obvious that this method of dispensing cream will create a great saving in time and labor and meet the increasing demands for hygienic methods of dispensing cream and like merchandise.

It is to be understood that the form of my invention herewith shown and described is to be taken as the preferred example of the same, and that various changes in the shape, size, and arrangement of parts may 110

be resorted to, without departing from the spirit of my invention or the scope of the subjoined claims.

Having thus described my invention, I 5 claim:

1. A dispensing device of the character described, comprising a cylindrical shell, a plunger movably mounted within said shell, a rod secured to said plunger, a knife blade 10 positioned beneath said plunger, a second rod connected to said knife blade, a hand wheel attached to said second mentioned rod for revolving said knife blade, and a handle attached to said first mentioned rod for reciprocating said plunger in said shell, said 15 handle and hand wheel being so arranged that the fingers of the operator's hand that grips said handle may be used to rotate said hand wheel.
2. A dispensing device of the character 20 described, comprising a cylindrical shell, a

plunger head movably mounted within said shell, a tubular rod secured to the head, a knife blade positioned beneath the plunger head, a second rod positioned in said tubular 25 rod and connected to the knife blade, a hand wheel attached to said second mentioned rod for revolving the knife blade, and a loop shaped handle arranged about said hand wheel and attached to said tubular rod 30 for reciprocating the plunger head in the shell, said loop shaped handle being so arranged about said hand wheel that the fingers of the operator's hand that grips said loop shaped handle may be used for 35 rotating said hand wheel.

In testimony whereof, I have affixed my signature in the presence of two witnesses.

EDWARD L. STAHLÉY.
